UNITED STATES PATENT OFFICE.

ARTHUR J. MOXHAM, OF JOHNSTOWN, PENNSYLVANIA.

PROCESS OF ROLLING STEEL OR IRON.

SPECIFICATION forming part of Letters Patent No. 408,843, dated August 13, 1889.

Application filed January 25, 1889. Serial No. 297,557. (No model.)

To all whom it may concern:

Be it known that I, ARTHUR J. MOXHAM, of Johnstown, county of Cambria, and State of Pennsylvania, have invented a new and useful Improvement in the Process of Rolling Iron or Steel, of which the following is a true and exact description, due reference being had to the drawings which accompany and form part of this application, and in which 10 similar letters denote similar parts.

Heretofore the process of rolling these metals consisted in passing them through a pair of rolls grooved to the conformation desired. The piece is made to pass through said rolls 15 by the adhesion or bite of the rolls when the rotary movement is given to the rolls. The piece is thus fed in and travels with a speed due to the surface velocity of the rolls. I have discovered that I can produce a difference of 20 extent in the actions of the rolls upon a piece of metal passed through if I exert a force upon the piece in its passage through the rolls, said force being in the direction of the surface motion imparted by the rolls, instead 25 of passing it through the rolls, unaccelerated, with the surface motion of the rolls.

My improvement consists in exerting a pressure or force of any desired extent during the movement of the piece through the rolls in 30 the same direction as that of the surface motion imparted by the rolls. I carry out this process by the addition to the ordinary system of rolls of mechanism which will exert a force upon the piece during its passage through 35 the rolls in the same direction as that of the surface motion of the rolls, so that while the spreading and elongation of the piece are effected by the rolls the piece will not pass through the rolls simply by the surface motion 40 imparted by the rolls. Various mechanisms can be used to accelerate the passages of the piece, one form of which is shown in this application.

In the drawings, Figure 1 is a general side 45 elevation showing pair of forming-rolls of any desired conformation, the piece to be acted upon, and the mechanism by which the piece is acted upon by the desired accelerating force. Fig. 2 is a front elevation in detail from line $x-x$ in direction of arrow; Fig. 50 3, a section on lines $y-y$, Fig. 2.

R R are the forming-rolls, of any desired conformation.

N N are the delivery or feeding rolls, by the movement of which the piece is brought 55 to the entrance of the forming-rolls.

B is a frame of sufficient solidity mounted on the wheels B', which wheels rest and travel upon the tracks C. Projecting from and secured to this frame B is a support D, 60 d being rods to strengthen or brace this support. Securely suspended in this support D is the pair of gripping-rolls E F, the roll E being set true, while the roll F is slightly eccentric.

K K are the upper collars of these rolls, provided with a series of holes $k-k$.

H is a projection from the frame B and rigidly secured thereto. h is a wire rope or cable of sufficient strength, which is secured to 70 said projection and passes over the drum I.

J is a cylinder having the piston-head j and piston j' .

j^2 is a cable or chain connecting the piston with the drum H.

G is a valve for admitting water or steam from the source of pressure-supply to either side of the piston-head by pipes $g-g'$.

L is the piece to be acted upon.

The operation is as follows: The piece to 80 be acted upon is gripped at its rear end between the rolls E and F and its front end brought in line with the mouth of the forming-rolls. The steam or water is then admitted to the cylinder and the piston caused 85 to travel in the direction denoted by the arrow. The frame B is pulled forward upon the track C by the action of the piston on the drum H, which drum, being of large size, causes the frame B to move with a greater or 90 less force, dependent upon the size of the drum and the pressure on the piston-head, and the piece is thus caused to pass through the rolls with a force exerted upon it in the direction of the surface motion imparted by 95 the rolls' rotation. When the piece has passed almost entirely through the rolls, the frame B strikes the projection M at the side of the track C and stops the further movement of the frame, and the rolls R R pull the 100 piece from between the gripping-rolls and it entirely passes through the rolls. The valve

may be changed automatically at this point or by any means and the water or steam admitted to the other side of the piston-head, when the weight W, acting through the drum 5 V and cord or chain X, will return the frame to its initial point and in position for further action, (the frame B on its forward movement having raised this weight W.) The weight W, as may be readily understood, is 10 very light, and it is only necessary that it shall be sufficient to return the frame B. By varying the size of the drum or the pressure of water or steam in the cylinder a greater or less force may be exerted upon the piece. By 15 my improved process of rolling I am enabled to obtain different and improved results and to vary the results of the roll action upon any given portion of the piece.

It is obvious that many different mechanisms 20 may be used to carry out this process of rolling, and I do not intend to limit myself to

the hereinbefore-described mechanism or any particular mechanism. It is also obvious that the mechanism can be located in front of the main rolls and exert its accelerating action by 25 a pull, instead of being located behind the same and doing so by a push; but

What I claim is—

An improved process of rolling metal, which consists in exerting a pressure or force upon 30 the piece in the direction of the surface motion imparted by these rolls during the passage of the piece through the rolls.

In testimony of which invention I have hereunto set my hand, at Johnstown, county 35 of Cambria, State of Pennsylvania, this 18th day of January, 1889.

ARTHUR J. MOXHAM.
